SWITCH STRUCTURE

Frederick C. Byram, Springfield, Ohio, assignor
to Penberthy Injector Company, Detroit, Mich.,
a corporation of Delaware

Application November 11, 1936, Serial No. 110,229

1 Claim. (Cl. 200—67)

My invention relates to switch structures adapted particularly for snap closing or opening of electrical circuits.

An important object of the invention is to provide an improved structure comprising a switch control element either manually or automatically operable, a switch actuating element, and a spring toggle link between the elements, with the operation such that during a period of movement of the control element the spring toggle is loaded for subsequent quick or snap movement thereby of the switch actuating element for operation of the switch.

A further important object of the invention is to provide a simplified structure comprising a swinging control element and a swinging switch actuating element, with a common pivot support for these elements and with a spring toggle link interposed between the elements for snap action of the switch actuating element after a period of movement of the control element.

The invention also incorporates other features of structure, arrangement and operation.

A structure embodying the various features of the invention is shown on the accompanying drawing, in which drawing:

Figure 1 is a side elevation;

Figure 2 is an end elevation;

Figure 3 is a section on plane III—III of Figure

30 2, with the control element in its upper position;

Figure 4 is a section similar to Figure 3, with

the control element in its lower position;

Figure 5 is a section similar to Figure 3, with

the control element in neutral position; and

35 Figure 6 is a side elevation like Figure 1 but

with the switch bulb and supporting bracket re-

moved.

In the structure shown, a supporting base plate 10 of sheet metal has its upper portion bent forwardly to form a top wall 11 whose forward portion is bent downwardly to form a wall portion 12 parallel with the base plate. Extending transversely through the base plate and the front wall 12 is a pivot pin 13, and between the base plate 14 and front wall the pin journals a hub 14 secured to and supporting the control element 15 shown in the form of a lever formed from a piece of sheet metal. At its outer end the lever has the laterally deflected flange 16 by which it may be manipulated or actuated. As shown, the body of the lever is diamond-shaped, its upper edges on opposite sides of the pivot abutting with the top wall 11 so that the range of swing of the lever is limited.

55 The switch actuating element 17 comprises in-

ner and outer parallel arms 18 and 19 connected together at their lower ends by a yoke 20, and the actuating element may, as shown, be formed up from a single piece of sheet metal. At their upper ends the arms receive the pivot pin 13 so that the element 17 is supported for swinging movement. The inner arm is adjacent to the base plate 10 and the outer arm is outside of the wall 12, and a washer 21 may be inserted between the inner arm and the base plate to reduce friction.

The lever 15 at the lower point of its body has an ear 22 extending therefrom which receives the bifurcated head 23 of the toggle link 24 for pivotal connection therewith by means of a pin 25. The body of the link is cylindrical and has the 15 longitudinal slot 26 which receives the bar or pin 27 secured to and extending between the outer ends of the arms 18 and 19 of the actuating element 17. A compression spring 28 encircles the link body with one end abutting the bar 27 and the other end abutting the shoulder 29 at the base of the bifurcated head 23 of the link.

The inner arm 18 of the actuating element 17 has an opening 30 therethrough into which projects a stop tongue 31 which may be formed by deflecting forwardly a portion of the base plate 10. The engagement of the sides of the opening 30 with the stop tongue limits the range of swing of the actuating element 17.

The extension 22 on the lever 15 and the toggle link and spring constitute a spring toggle connection between the lever and the switch actuating element for effecting quick or snap action of the actuating element when the control element or lever 15 is operated. Referring to 30 Figures 1 and 3, where the lever 15 is in its upper position, the axis of the pivot pin 25 is to the right of the dead or neutral line between the pivot pin 13 and the bar 27, and the actuating element 17 will be held with the right side of the opening 30 against the stop tongue 31. If the lever 15 is now swung downwardly, the actuating element 17 will not be moved until the pivot connection 25 between the lever and the toggle link has moved to the left beyond the dead or neutral 45 line between the pivot pin 13 and the bar 27. During downward swing of the lever the spring is compressed and loaded, and then, after passage of the pivot 25 beyond the neutral line, the force of the loaded spring will be expended in 50 quickly moving or snapping the actuating element 17 to the right, and in quickly swinging the lever downwardly through the remainder of its downward movement, the actuating element being stopped by the engagement of the left side 55

of its opening 30 with the stop tongue 31, and the lever being stopped by the engagement of the inner end thereof with the top wall 11 of the supporting base. Figure 5 shows the movement of the toggle element through the neutral line, and Figure 4 shows the final position thereof, with the control lever down. If the lever is now swung upwardly, the actuating element remains at rest until the toggle link pivot 25 passes the neutral line, whereafter the actuating element 17 will be quickly moved or snapped to the left, with the right side of its opening 30 against the stop tongue 31, and the lever 15 will be quickly returned to its full upper position where it will be stopped by its engagement with the top wall 11. The initial movement of the control lever in either direction thus loads the toggle spring, and thereafter the actuating element and the control element are quickly snapped to their respective limits of movement.

I have shown the actuating element 17 arranged to support and actuate a mercury tube switch 34. To support the mercury tube, a portion of the outer arm 19 of the actuating element 25 may be bent forwardly to provide a shelf 32 for supporting a spring clamp 33 for the tube 34. As shown on Figure 1, the tube or bulb 34 may have circuit terminals A and B for connection by the mercury C when the control lever 15 is 30 in its upper position for closure of the circuit of an operating element such as an electric motor. When the lever is swung downwardly and the toggle connection swings the actuating element 17 into its other position, the mercury tube is 35 canted for disconnection of the mercury from the contacts and reopening of the circuit. The mercury bulb may have terminals D and E at its other end for closure of another circuit when the bulb is tilted, or other terminal arrangements 40 may be provided for any desired control of one or a number of circuits. The quick or snap action of the element 17 and the consequent rapid tilting of the switch bulb will assure quick opening and closing of the circuit to be controlled. 45 The switch structure shown comprises simple parts, mostly of sheet metal, which can be economically made and assembled. The provision of a common pivot support for the control ele-

ment 15 and the actuating element 17 materially simplifies the construction, and with the toggle arrangement shown there is an ample side thrust component against the actuating element to hold it in snapped position against accidental displacement.

The flange 16 on the control lever 15 facilitates manual actuation of the lever, and the flange may be slotted as indicated at 36 for engagement with suitable abutments on shift rods or wires 10 (not shown) for transmission to the lever of the movement of control elements such as floats, and for resultant control by the switch structure of electrical circuits of driving motors of devices whose operation is to be regulated.

I have shown practical and efficient embodiments of the various features of my invention, but I do not desire to be limited to the exact construction, arrangement and operation shown and described, as changes and modifications may be 20 made without departing from the scope of the invention.

I claim as my invention:

In a switch structure of the class described, a supporting frame comprising a back wall, a top 25 wall, and a front wall depending from the top wall, a pin supported by said back wall and front wall, a hub journaled on said pin between said front and back walls, an actuating lever carried by said hub to swing on said pin, a U-shaped 30 switch actuating frame having its rear leg receiving said pin between said hub and said back wall and having its front leg receiving said pin in front of the front wall, said front leg having a portion deflected laterally thereupon to form a 35 support for a circuit controlling element, an abutment pin connecting said switch actuating frame legs near the yoke thereof, a toggle link structure comprising a link having a head pivoted to said lever and having a slot in its other end 40 receiving said abutment pin, a spring encircling said link and abutting said abutment pin and said head, whereby swing of said lever will result in snap swing of said switch actuating frame, and circuit controlling means carried by said 45 switch actuating frame.

FREDERICK C. BYRAM.
